UNITED STATES PATENT OFFICE.

LOUIS HORNBERGER, OF BRIDGEPORT, CONNECTICUT, ASSIGNOR TO THE BRIDGEPORT BRASS COMPANY, OF SAME PLACE.

DESIGN FOR A BICYCLE-LANTERN.

SPECIFICATION forming part of Design No. 28,080, dated December 21, 1897.

Application filed March 26, 1897. Serial No. 629,462. Term of patent 7 years.

To all whom it may concern:

Be it known that I, LOUIS HORNBERGER, a citizen of the United States, residing at Bridgeport, Connecticut, have invented a new and original Design for Bicycle-Lanterns, of which the following is a specification.

In the accompanying drawings, Figure 1 is an elevation of my bicycle-lantern, showing my design. Figs. 2 and 3 are plan views, respectively, of the top and bottom of said lantern.

The same numerals refer to like parts in the several views.

1 designates the top of the lantern, the center of which is an embossed perforated circle divided by a band, shown as plain, but which may contain a name or trade-mark designation of the lantern. Around this circle is a series of radial foliations on a stippled ground-work.

2 is a vertical band carrying a reeded bead. 3 is a vertical cylindric portion of less diameter than said band, embossed with a scroll pattern.

25 4 is a reeded bead, beneath which is an open cylindric portion 5, beneath which is a third reeded bead 6.

The parts so far described constitute a cap or top detachably secured to the body 7.

30 7 is a cylindric body pierced for the cone 8 and having a foliated embossing around such opening. The cone 8 has a series of radial lines of varying lengths on its surface and has its open end ornamented by an embossed

annulus. The body 7 is also pierced on each side for a window 9 and has a scroll on its surface above and beneath each of said windows. At the lower edge of the body 7 is a reeded bead. Separating the body 7 from the fount 12 is a perforate band 11, lightly connected to both body and fount. The fount 12 is of conical shape and has two reeded beads inclosing a band of alternate medallions and scallops. The bottom 13 of the fount 12 has a central opening surrounded by a radial foliated em- 45 bossing.

The leading features of my design are found in the parts particularly specified and pointed out in the claims.

The general design of the lantern is of the 50 "Empire" style and includes medallions and foliated and scrolled ornamentations.

What I claim is—

1. The design for a bicycle-lantern, substantially as shown and described. 55

2. In a bicycle-lantern the design for the top or cap thereof, substantially as shown and described.

3. In a bicycle-lantern the design for the body thereof, substantially as shown and de- 60 scribed.

4. In a bicycle-lantern the design for the fount thereof, substantially as shown and described.

LOUIS HORNBERGER.
